(57) **CLAIM**

The ornamental design for an upper portion of a chair, as shown and described.

DESCRIPTION

FIG. 1 is an environmental perspective view of an upper portion of a chair showing my new design;

FIG. 2 is a top plan view thereof;

FIG. 3 is a front elevational view thereof;

FIG. 4 is a right side elevational view with the left side being a mirror image thereof; and,

FIG. 5 is a rear elevational view thereof.

The broken line showing of the chair legs in FIGS. 1, 3, 4, and 5 is for illustrative purposes only, merely disclosing the types of legs which may be used, and forms no part of the claimed design. The bottom view is plain and unornamented.
